SPACE CONDITION RESPONSIVE INSTRUMENT

Leonard B. Olsen, Minneapolis, Minn., assignor to
Minneapolis-Honeywell Regulator Company, Minne-
apolis, Minn., a corporation of Delaware

Application June 12, 1957, Serial No. 46,561

Term of patent 14 years

(Cl. D52—7)

FIG. 1

FIG. 2

Figure 1 is a front perspective view of a space condition responsive instrument showing my new design, and

Figure 2 is a side elevational view of the instrument shown in Figure 1.

The dominant features of the design reside in the portions shown in solid lines.

I claim:

The ornamental design for a space condition responsive instrument, as shown and described.
